UNITED STATES PATENT OFFICE

150,354

DESIGN FOR A CIGARETTE AND CIGAR CASE

Stanley J. Glowiaak, Fresno, Calif.

Application June 4, 1946, Serial No. 130,479

Term of patent 14 years

(Cl. D85—2)

To all whom it may concern:

Be it known that I, Stanley J. Glowiaak, a citizen of the United States, residing in the city of Fresno, county of Fresno, and State of California, have invented a new, original, and ornamental Design for Cigarette and Cigar Cases, of which the following is a specification, reference being had to the accompanying drawing, forming part thereof.

Fig. 1 is a side elevational view of a cigarette and cigar case, showing my new design.

Fig. 2 is a front elevational view of said case.

Fig. 3 is a rear elevational view of the same.

Fig. 4 is a side elevational view of the case illustrating the side opposite thereof from that shown in Fig. 1.

I claim:

The ornamental design for a cigarette and cigar case, as shown.

STANLEY J. GLOWIAAK.
